TRAFFIC CONTROL SYSTEM AND APPARATUS

Harry A. Wilcox, Bronxville, N. Y., assignor to
Automatic Signal Corporation, New York, N. Y.,
a corporation of Delaware

Application February 20, 1936, Serial No. 64,841

20 Claims. (Cl. 177—337)

This invention relates to traffic control systems for interfering traffic lanes, particularly to those systems of the traffic actuated type in which vehicles, pedestrians, or other traffic elements indicate their presence to a traffic signal controller through traffic detectors and influence the timing of traffic signals, and is especially concerned with means for supervising the operation of individual systems of that type at different intersections so as to provide for coordinated movement of traffic passing successively through the several different intersections.

Systems are well known in the prior art for supervision of individual local traffic signal controllers of the so-called fixed time or non-traffic actuated type by some form of master controller to resynchronize the local controllers periodically so as to maintain a predetermined simultaneous or sequential progressive relation between the times of transfer of right of way between the intersecting streets at the different intersections, and thus provide for coordinated movement of traffic through the several intersections.

Traffic actuated control systems for the control of individual or isolated street intersections have also been in use for several years and more recently arrangements have been employed to supervise the transfer of right of way from a main highway to a cross road by a traffic actuated signal controller in response to actuation of such controller by traffic on the cross road to coordinate such transfer with any corresponding transfers occurring at other intersections. Such supervision has been usually in the form of a common master timer with connecting circuits to several individual local intersection traffic signal controllers for restricting the transfer of right of way from the main highway at one or more of such individual intersections in response to traffic actuation on the respective cross roads at the latter. In such systems the right of way normally remains continuously on the main highway in the absence of cross road actuation. The master timer cyclically opens and closes such circuits for example for predetermined periods to control when the local controllers can and cannot respond to traffic actuation and thus coordinates the actions of the different local timers for the benefit of through highway traffic.

The master timer has in some cases been a single centralized control and in other cases has been in the form of individual synchronous motor driven master timers associated with the individual local signal controllers, the synchronous motors maintaining the individual master timers

in step by connection to a common A. C. power line.

In such systems of supervisory control the cycle of open and closed circuit conditions provided by the master controller for any local controller may be termed the "master control cycle" or the "background cycle." This cycle may be arranged to accord alternate "permissive" and "preventive" periods of control over transfer of right of way from the main highway by the local controller. The "permissive period" is the period provided cyclically by the master control and during which the local controller can transfer right of way to its cross road if traffic actuation at its cross road has occurred. In a total background cycle of 60 seconds for example this permissive period might range in length from 5 to 30 seconds, the length selected for a particular intersection depending on the traffic conditions there and its relation to the coordination plan for all intersections.

The "preventive period" is generally the complement of the permissive period, as when the permissive period for cross road traffic is 10 seconds out of a 60 second background cycle for example, the preventive period would ordinarily be the remainder of the cycle or 50 seconds.

The "permissive" and "preventive" periods may either be arranged to cause all local controllers that have been actuated by traffic to transfer right of way substantially simultaneously, or they may be arranged to cause right of way to be transferred at the several intersections in progressive sequence to provide progressive traffic movement down the highway.

It has been found with these prior systems of supervisory control, where the point of control of the master timer over the local timer is at that point in the local timer's signal cycle where right of way is transferred to the cross road, that the "permissive period" during which the local timer can respond to cross road traffic actuation and transfer right of way to the cross road must be quite short, since the longer this period is made the more chance there is for the local timer to transfer right of way to the cross road later than the best time for coordinated movement, and if the period of right of way accorded to the cross road is required by cross traffic to be fairly long, the amount of delay in transferring right of way to the cross road will also be reflected in returning right of way to the main highway. The right of way return to the main highway may thus be carried over into that portion of the background cycle assigned for main highway right of way and traffic arriving at the

intersection on the main highway in progressive movement thereby interfered with and delayed.

This new system overcomes these difficulties and provides in accordance with the invention an arrangement for causing the return of right of way to the main highway by the local controller as least as early as the beginning of the main highway right of way period of the background cycle, so that even though the permissive period is quite long and the right of way is transferred to the cross road quite late in the portion of the background cycle assigned to the cross road the return of right of way to the main highway at the proper point in the background cycle will be assured by supervisory action of the master timer on the local timer. Thus in accordance with the invention the permissive period for transfer of right of way to the cross road may be made to extend through a large part of the cross road right of way portion of the background cycle, and thus cross road traffic actuating the local controller is given a longer opportunity to initiate right of way transfer for its benefit.

The earlier traffic actuated control systems subject to supervisory coordination control of the "permissive" type mentioned were in some cases provided with means in the local controllers for varying the cross road right of way period between a minimum and a maximum depending on the demand of cross road traffic as shown by traffic actuation, during the cross road period. This flexibility of the local controller however offered a problem in coordinated control systems because it increased the possibility of right of way being held on the cross road over into the main highway portion of the background cycle. This difficulty is also overcome by the invention in assuring that variation of the cross road right of way period cannot carry beyond the end of the cross road right of way portion of the background cycle.

Another limitation in past systems has been that supervisory control only of the transfer of right of way from the main road to the cross road offers no effective way of co-ordinating two local controllers where one or both were of the full actuated type.

It will be appreciated at this point that the so-called main and cross roads may have substantially equal traffic, or the traffic on the cross road might at times exceed that on the main road. The terms main road or highway and cross road are therefore to be construed generally with full actuated control and not necessarily to infer always that the main highway has more traffic than the cross road.

The terms "semi-traffic actuated" and "semi-actuated" control systems are used herein to designate a traffic control system for an intersection in which traffic actuatable devices are located only in the cross road, the right of way being normally accorded to the main road in the absence of actuation on the cross road, and being transferred to the cross road in response to cross road traffic actuation, and after a period which may vary between a minimum and a maximum in accordance with traffic actuation, being retransferred automatically to the main road.

The new system arranged in accordance with the invention provides means of controlling from the master controller both the transfer of right of way from each street and the return transfer of right of way to each street by the local controller at appropriate points of the background cycle of the master controller, these functions

being provided in cooperative relation so as to restrict the transfer of right of way only so far as required in each cycle to enable the local controller to be in condition at these appropriate points in the background cycle to transfer right of way to the proper streets if such transfer should be required by traffic actuation, and to allow the local controller to transfer right of way and maintain right of way throughout the remainder of the background cycle in accordance with the demand of traffic as shown by traffic actuation. Thus the invention provides as will be later described in detail that a number of individual flexible traffic actuated controllers of either the full actuated or semi-actuated type or both may be coordinated in a manner to assure that in the presence of traffic the right of way will be accorded to the proper street at the proper time in accordance with the predetermined coordinated plan of the background cycle, but that as traffic varies from the pattern of the background cycle the local controller will be permitted to vary the proportions of time right of way is accorded to the intersecting streets.

It is an object of this invention to provide an improved system for coordinating the operation of a plurality of individual traffic actuated traffic signal controllers at a number of intersections of interfering traffic lanes to promote the smoother movement of traffic successively thru the several intersections.

It is another object of the invention to coordinate the operation of individual traffic actuated controllers at different intersections so as to favor the movement of traffic thru the several intersections in accordance with a predetermined coordinated plan, but also to provide a high degree of flexibility for the individual controllers to depart from that plan insofar as traffic at such individual intersections differs from that on which the plan was based.

It is an additional object of the invention to supervise cyclically the accord of right of way by a traffic actuated signal controller at an intersection so as to favor the accord of right of way to one street at the intersection during one portion of a time cycle when traffic is present on that street during that portion of such cycle.

It is a further object of the invention to supervise cyclically the accord of right of way by a traffic actuated signal controller at an intersection so as to favor the accord of right of way to one street at the intersection during one portion of a time cycle and to favor accord of right of way to an intersecting street during another portion of the time cycle when traffic is present on the particular street in its respective portion of the time cycle.

It is another object of the invention to supervise a traffic actuated signal controller at an intersection in accordance with a master control cycle such that during a portion of such cycle the arrival of traffic on a preferred street at the intersection while right of way is being accorded to another street will cause substantially immediate transfer of right of way to the preferred street.

It is also an object of the invention to supervise a traffic actuated controller at an intersection so that cyclically for predetermined periods the transfer of right of way from a preferred lane to an intersecting lane is prevented if it has not previously occurred, and during the latter portion of said period the transfer of right

of way to such preferred lane from such intersecting lane is required in the presence of traffic on such preferred lane if right of way has been on such intersecting lane regardless of traffic actuation demand on such intersecting lane.

It is a further object of the invention to supervise a traffic actuated controller as described in the last mentioned object but providing such cyclic predetermined periods successively for the different lanes so that during a part of the cycle one lane is made the preferred lane and during another part of the cycle an intersecting lane is made the preferred lane.

It is another object of the invention to provide a traffic control system in which individual signal timers at different intersections along a preferred street are arranged to be fully actuated by vehicles on the preferred street and on a cross street but in which a progressive movement of traffic along the preferred street will be favored by assuring that at and immediately prior to the time when a group of vehicles in the progressive movement on the preferred street are scheduled to arrive at each intersection if the individual timer at that intersection is according right of way to the preferred street the transfer of right of way from the preferred street will be prevented, and if the individual timer is according right of way to a cross street the transfer of right of way to the preferred street will be assured in time to avoid stopping any vehicles to arrive in such group.

It is a further object of the invention to provide a traffic control system in which traffic signal timers at individual intersections along a main street normally accord right of way to the main street but upon actuation by traffic on a cross street transfer right of way to such cross street for a period which may be dependent upon the amount of traffic actuation on that cross street and thereafter retransfer right of way to the main street, and in which coordinated movement of traffic along the main street is provided for by providing a cycle of supervisory control over the individual timers in a predetermined portion of which right of way is assured to the main street, the transfer of right of way to the cross street being permitted only during a certain portion of the cycle, and the retransfer to the main street being assured before the beginning of the main street predetermined assured portion of the cycle.

It is another object of the invention to provide a traffic actuated signal control apparatus for an individual intersection which is adapted to fit into fixed time or non-traffic actuated progressive systems along a preferred street passing thru this intersection, the transfer of right of way by the apparatus from the preferred street being permitted only during a predetermined portion of the time cycle of the fixed time progressive system and the accord of right of way to the preferred street being assured either positively or in the presence of traffic on the preferred street during another portion of such time cycle.

It is also an object of the invention to provide, in association with a traffic actuated signal control system which accords right of way alternately to intersecting traffic lanes between minimum and maximum time limits in accordance with traffic actuation on such lanes, a mechanism for connecting such systems to a fixed time or other cyclic supervisory system so that during a certain portion of the supervisory cycle the maximum time limit is shortened to force the

prompt transfer of right of way to a preferred traffic lane in case right of way is on an intersecting traffic lane.

Other objects will subsequently appear and considering now one form of apparatus embodying the invention, reference may be had to the following figures in which:

Figure 1 illustrates a series of intersections along a street on which coordinated traffic movement is desired, the several intersections being equipped with different types of traffic control apparatus interconnected to be supervised in accordance with the invention.

Figure 2 illustrates how apparatus may be placed in accordance with the invention to provide coordinated traffic actuated control throughout a grid of intersections, providing for coordinated movement of traffic through both north-south and east-west series of intersections for example.

Figure 3 shows a schematic diagram of a time cycle of supervisory control for a fully traffic actuated traffic signal control system at a typical intersection in accordance with the invention.

Figure 4 shows a time cycle of supervisory control for a semi-traffic actuated signal control system at a typical intersection.

Figure 5 is a schematic circuit diagram of an illustrative form of a full traffic actuated traffic control system at a typical intersection and its supervisory control embodying the invention.

Figure 6 is a schematic circuit diagram of one form of semi-traffic actuated control system at another intersection and its supervisory control embodying the invention.

Figure 7 shows an alternative form of supervisory control of a full traffic actuated system.

The significance and operation of the new system of this invention may perhaps best be understood by visualizing it as comprising individual traffic actuated signal control systems at each of a number of intersections with a so-called fixed time or non-actuated progressive system superimposed, the traffic actuated systems having the direct control of the signals, and the progressive system providing cyclic control in the background over the traffic actuated systems so as to favor the accord of right of way for example first to the main street in one part of the progressive system cycle and then to the cross street in another part of this background cycle—in effect cyclically making first one street and then the other a preferred street, in predetermined simultaneous or sequential time phase at the several intersections.

This supervisory effect of the progressive system background cycle can be made operative on the traffic actuated controller so that during substantially the entire portion of the background cycle during which right of way would ordinarily be accorded to one street by the progressive system the transfer of right of way from that one street to the other street in response to actuation on the latter is prevented, and correspondingly during the portion of the background cycle assigned for right of way to such other street the transfer of right of way to the one street is prevented. This effect can be supplemented by having the progressive system force immediate transfer of right of way to the preferred street in its portion of the background cycle in response to any traffic actuation on that street. The combination of these two effects is to cause the right of way to be accorded to the respective streets by the traffic actuated controller in accordance

with the fixed time progressive cycle as long as traffic is present on the respective streets.

Having these effects operative during the entire portion of the background cycle assigned to a preferred street however is principally of benefit in the semi-traffic actuated type of operation where the main street is the preferred street. For full traffic actuated operation these supervisory effects are preferably made operative only long enough in each portion of the background cycle as to assure the accord of right of way to the preferred street at the beginning of its period in the presence of traffic, the traffic actuated controller then being released from the supervisory control effects for substantially the balance of the period for the preferred street, the right of way being controlled after such release solely by traffic demand, traffic actuation on the preferred street holding the right of way and traffic actuation on the intersecting street causing transfer of right of way from the preferred street as soon as traffic ceases for an appreciable period on the latter street. It will be understood the intersecting streets will be alternately treated as the preferred street for predetermined portions of the background cycle.

The use of the apparatus of the invention will be described and shown applied both to full and to semi-traffic actuated traffic signal controllers, and also to non-traffic actuated controllers.

Referring now to Figure 1 there is represented a series of intersections of a common street A with cross streets, each of the intersections shown being provided with a traffic signal and controller therefor which may for instance be of the types designated in the figure. Traffic actuatable detectors are placed in the intersection approaches where desired and connected to the proper signal controller. A master controller is also shown, comprised of a series of contact discs or other suitable contact devices continuously driven in synchronism by a motor M which is preferably of a constant speed type. By means of the contact discs, supervisory control circuits to the controllers at the several intersections shown are completed and interrupted in certain parts of the cycle of the contact discs in a predetermined arrangement. Similarly the control circuits to controllers at other street intersections may be made and broken by properly designing the contact disc segments. It will be understood that all the intersections might be equipped with full actuated controllers or semi-actuated, or any combination required for adequately serving the series of intersections in question. It will also be obvious to those skilled in the art that pedestrian push buttons or switches could be connected to the controllers for actuation by pedestrians to supplement or take the place of vehicle actuation, and trolley contactors or other well-known forms of street car or railway actuating devices might be employed for such traffic as well as automotive or other road traffic. The term traffic is therefore to be considered as broadly including all such traffic elements.

Figure 2 represents the installation of a system of this general character to a grid or checkerboard of intersecting streets showing a number of full traffic actuated, semi-actuated and non-traffic actuated signal controllers and their connections to a master controller for supervising the cycles of all the individual intersection controllers. The control circuits from the master to the supervisory control relays at each controller

5 may be arranged to be energized at the proper times to permit progressive movement of traffic in both directions on each of the streets in the group. Further explanation of such signal operation as well as the method of accomplishing it will be described below.

10 Referring now to Figs. 3 and 4 the schematic cycle diagrams for the background supervisory control time cycle as applied to two types of local signal controllers show the interrelation of the several portions of the supervisory cycle and their significance in connection with the preferred right of way signal periods of the background cycle (right of way being indicated in the figure as R. O. W. to conserve space).

15 Figure 3 shows one preferred form of supervisory cycle to be applied to a full-traffic actuated local controller as illustrated at the intersection of A and B streets for example in Fig. 1 and Fig. 5. Beginning at the top at the point O the time cycle can be traced clockwise around the circle passing the point marked T and returning to O and repeat. The radial lines at point O and T show the division of the background cycle into a portion O-T assigned for right of way to A street and a following portion 20 T-O assigned for right of way to B street. It will be understood that this is not the actual division of right of way signal display periods at the full traffic actuated control intersection but only the preferred division for best coordination with other intersections in the progressive system or other suitable complete control system for the entire group of intersections. In the case of a fixed time or non-actuated controller as for example at intersection Z however the division of right of way periods shown on the outer circle of the diagram is also the actual division of right of way by the signals. In the case of full traffic actuated control the actual signal displays do not normally correspond exactly with the division of the background cycle as shown on the diagram, but vary more or less from this division depending upon whether traffic is light or heavy respectively at the intersection. If traffic is very light for example and there is traffic on B street but no traffic on A street during the A street portion of the background cycle the right of way may remain on B street during a large part or all of the A street portion of the cycle. With substantially continuous traffic approaching on each street the actual signal display would correspond with the background cycle division and phase relations shown.

25 30 35 40 45 50 55 60 65 70 75 The supervisory control thus primarily favors the transfer of right of way to and the holding of right of way on first one street and then the other by the local traffic actuated controller. These effects can be seen by further reference to Fig. 3, considering for example the point T at which transfer of right of way from A street to B street is to be favored by the supervisory control. It will be noted that prior to the point or line T there is a period extending from the point or line BP to T designated as the B street preparatory period. During this period no transfer of right of way from B street is permitted (if right of way is already on B street), but transfer of right of way to B street (if right of way is on A street) is not yet forced. Thus if right of way is on A street during this period it may be held there by actuations of traffic on A street but if right of way is on B street it cannot be transferred to A street during this period.

Ordinarily the time interval of this prepara-

tory period is set to correspond with the minimum time required in accordance with the normal time intervals of the individual local controller to transfer right of way to A street and back to B street. For example if the yellow interval after B street right of way is 3 seconds, the A street initial green interval is 5 seconds, the A street vehicle interval given is 5 seconds and the yellow interval after A street right of way is 3 seconds the sum of these intervals or 16 seconds is the shortest normal time in which right of way can be transferred from B street and be returned to it, and the B street preparatory period is correspondingly set at 16 seconds. The preparatory period may of course be set longer than the sum of these several intervals as described but it is preferably not set any shorter, so as to avoid the possibility of transfer of right of way from B street so late in the B street portion of the background cycle that right of way will not be returned to A street at the beginning of the B street portion of the cycle.

After passing the point T in the supervisory cycle in Fig. 3 it will be seen that a "right of way guarantee period" for B street is provided, extending to the line BG. This is the portion of the cycle in which right of way is assured to B street if any traffic is present on B street as shown by actuation of the B street detectors. It can also be arranged to have automatic transfer of right of way to B street at the beginning of this period even without B street traffic actuation if desired as will be more fully explained subsequently herein.

Preferably however the supervisory control is arranged so that if right of way is on A street at the beginning of this B street right of way guarantee period and no traffic actuation has yet occurred on B street the right of way will continue on A street to care for any further traffic on A street. As soon as the first vehicle arrives on B street during this guarantee period however transfer of right of way to B street is caused immediately by the supervisory control in spite of any traffic on A street. Correspondingly if a vehicle is waiting on B street while right of way is held by traffic on A street at point T immediate transfer of right of way to B street is caused through the supervisory control. In each case such transfer preferably includes the usual yellow clearance period.

During the B street right of way guarantee period the transfer of right of way to A street is still preferably prevented by the supervisory control so that when right of way is on B street during this period it will be held to the point BG to care for the arrival of a group of vehicles which may be lagging behind the front of a progressive wave for example. Also in cases where a progressive wave of vehicles eastbound for example is scheduled to arrive some time after the westbound wave, this serves to hold the right of way on B street until the time when the eastbound wave is scheduled to arrive.

Thus it will be seen that two functions are performed by the supervisory control in connection with the preferred right of way transfer point T. First, during the entire period from BP to BG (i. e. the sum of B street preparatory period and B street right of way guarantee period) transfer of right of way from B street is prevented if right of way is on B street; and second, from T to BG (i. e. the B street right of way guarantee period) the transfer of right of way to B street is forced immediately upon B street

traffic actuation if right of way is not on B street.

It will be appreciated that either one of these functions could be employed alone to aid in causing a traffic actuated control system to fit into a progressive system pattern, both functions could be employed with more or less overlap of their periods than illustrated, but both functions are preferably employed for the periods illustrated.

Continuing around the cycle diagram in a clockwise direction the period from BG to O is designated as the B street traffic actuated right of way extension period during which traffic on B street may continue to hold the right of way. During the first part of this period, i. e. from BG to AP, the traffic actuated controller is free of any restrictions by the supervisory control. Thus during this period if right of way is on B street and traffic actuation occurs on A street, right of way may be held on B street only by closely spaced traffic on B street and if any considerable gap appears in traffic on B street the right of way will be transferred to A street to care for the traffic waiting there. On the other hand continuous traffic on B street can hold the right of way against any waiting traffic on A street until the point O is reached. However if traffic is very light and intermittent and the total supervisory cycle very long it is possible for right of way to be transferred from B street to A street and back to B street during the BG—AP period, the right of way remaining on either street to which it is transferred for a minimum period before it is retransferred.

Now at the point AP the supervisory cycle begins its preparatory period for A street right of way and if the right of way is on A street at point AP or thereafter in the AP—O period and O—AG period the transfer of right of way from A street is prevented. If the right of way is on B street however it may remain to the end of the A street preparatory period AP—O. During this period transfer of right of way to A street occurs through normal action of the traffic actuated controller upon any considerable gap in B street traffic occurring after any A street traffic actuation.

At the point O however and thereafter in the A street right of way guarantee period O—AG transfer of right of way to A street is forced immediately upon A street traffic actuation. As previously described for transfer of right of way to B street during the corresponding B street right of way guarantee period, the transfer of right of way to A street at point O can be made automatic if desired even in the absence of actuation on A street.

During the following period AG to BP the traffic actuated controller is free from restriction by the supervisory control and right of way may be held or transferred solely in accordance with the traffic demand on the respective streets as shown by actuation.

Referring now to Fig. 4 a corresponding supervisory cycle diagram for semi-traffic actuated operation as at A street-C street intersection is illustrated. In this case no traffic detectors are provided on A street and the right of way normally remains on A street in the absence of traffic actuation of the detectors provided on C street. The right of way is transferred by the traffic actuated controller upon actuation on C street and after a period of right of way on C street variable between minimum and maximum

limits in accordance with traffic actuation on C street, the right of way is transferred back to A street automatically.

In this case therefore there is no need for any supervisory control periods corresponding to the B street preparatory and B street right of way guarantee periods. The A street guarantee period is simply extended from the point O through the entire A street right of way portion of the background cycle to the point T corresponding to the similar point T of the Fig. 3 diagram, and the function of preventing transfer of right of way from A street is carried through this period.

Thus the period from the point T to AP serves as a permissive period for transfer of right of way to C street if C street traffic actuation occurs or has previously occurred in the A street portion of the cycle. In traffic actuation has not occurred on C street by the time point AP is reached however no transfer of right of way to C street can then occur until the end of the next A street guarantee period. No transfer of right of way to C street is permitted in the A street preparatory period AP to O, but as in the case of corresponding street B in Fig. 4 traffic on C street can continue to hold right of way on C street until the point O is reached. At the point O the transfer of right of way to A street is forced immediately (with the usual yellow clearance period) if such transfer has not already occurred. This forced transfer is automatic and occurs in spite of any traffic on C street at that time.

In this semi-actuated operation as well as in the full actuated operation above described however any traffic actuating the detector on any street within a short period just before any such forced transfer of right of way from that street is recorded and the effect of such actuation is stored so as to cause subsequent retransfer to that street without the necessity of further actuation there.

The operation of one complete embodiment of the invention in a full traffic actuated control system as illustrated at the intersection of A and B streets will now be described.

Reference is now had to Fig. 5 which is a circuit diagram of one embodiment of the full traffic actuated signal controller, together with its associated traffic signal, traffic detectors, supervisory control relays and connections to the master controller. It will readily be appreciated that this figure represents merely one embodiment of such a system and that the construction shown is for purposes of illustration only. It is believed that operation of the system will be understood most readily if there is presented first a description of the normal independent operation of a full traffic actuated controller of a type well known in the art and then a description of the supervisory control over such a traffic actuated controller provided by a master controller in accordance with the invention.

In Fig. 5 RNS, YNS, GNS, REW, YEW, and GEW represent colored signal lamps and lenses of conventional type for indicating stop, caution and go to the respective A street or north-south and B street or east-west intersecting lanes. Other types of signal indicators as semaphores, etc. might be used in lieu of the colored lamps shown. The portion of the apparatus within the dotted lines on the right side of the figure and labelled "Local controller" is the local traffic actuated signal controller for governing the op-

eration of the signal lights thru a cycle under the control of the traffic actuatable detectors DNS, DEW. The latter may be switches designed and located to be operated by the pressure of vehicles approaching the intersection, or they may be of a magnetic type in which the approach of the vehicle influences a magnetic field to change a circuit, or they may be of hydraulic or other suitable type. Pedestrian operated push buttons or switches may be suitably placed and wired in parallel with the vehicle switches if desired.

The local controller comprises essentially a battery of cams mounted on a common shaft and arranged to close cam contacts C1, C2 etc. in a particular order. The cam shaft is rotated step by step thru its cycle of six positions under the control of a solenoid S which is impelled at predetermined time periods by either of two condenser-gas discharge tube timing arrangements, one comprising gas discharge tube FJ and co-operating relay J, the other including tube FK and relay K; and their relation will be explained subsequently. The diagram at the right edge of Figure 2 shows by a black circle or bar which cam contacts are closed in each of the several cam shaft positions.

In the following description of operation of the traffic actuated controller through one complete cycle of signal indications it will be assumed that both the supervisory relays BS and AS remain de-energized and that the armatures of the relays complete circuits with their back contacts continuously. This is the normal position of these relays when the master controller is not operating and the individual intersection controllers are operating independently as for example when switch MCS in Fig. 1 is open, or when switches SAS and SBS in Fig. 5 are both open.

Connection I.—Assume both the switches HNS and HEW to be open, which is the mode of operation ordinarily employed.

Let it further be assumed that the controller is standing in cam shaft position 1, the yellow leaving NS signal position, where a circuit from A. C. positive lead 50 is completed over cam contact C21, lamp YNS to grounded lead 51, thus illuminating the yellow caution signal to the NS street and by a circuit over cam contact C11 from lead 50 through REW to 51, the red or stop signal is displayed to the EW street.

The length of the period of display of this signal indication is timed by a condenser-gas discharge timing arrangement. From D. C. positive lead 55, over cam contact C13, closed in this period, a circuit is completed thru adjustable resistance LNS leads 52, 53, condenser QJ to minus lead 51, thereby charging condenser QJ at a rate depending upon the line voltage existing between leads 55 and 51, the size of condenser QJ and the amount of resistance in the circuit.

The direct current for the timing functions of the controller are supplied from the alternating current mains to which the controller is attached by a rectifier VR or other convenient means. Such a rectifier may be arranged to operate as shown in conjunction with a transformer LXFR to obtain the desired value of direct current potential.

Considering once more the charging of the condenser QJ, it will be noted that all the factors in the charging of this condenser are constant during the operation of the controller with the exception of the amount of resistance in the

circuit, which may be varied by adjustment of the movable arm on resistance LNS. Consequently the length of this period, as well as other periods of the controller, may be predetermined by adjustment of the proper adjusting arm as will appear from the following description.

In parallel with condenser QJ there is a gas discharge tube FJ, a relay J, lead 54, and cam contact C8, which is closed in this position. The tube FJ is of such a character that normally it is non-conducting, but when the potential across its electrodes attains a certain predetermined value, or threshold conducting EMF, the gas within the tube ionizes and the tube suddenly becomes conducting. Discharge thru the ionized gas of the tube is maintained until the potential across the electrodes of the tube falls below a second predetermined value, much lower than the first, whereupon the ionization within the tube ceases and the tube again becomes non-conducting. Consequently when the potential across condenser QJ has reached the threshold conducting value of tube FJ, current passes thru the tube and thru relay J in series therewith to operate relay J momentarily.

At armature e_1 relay J completes a circuit from AC positive lead 50, lead 56, thru solenoid S via armature e_1 to minus lead 51, operating the solenoid momentarily. The solenoid advances the camshaft from position 1 to position 2. Also at armature e_2 operation of solenoid S completes a circuit thru low resistance RJ1 shunting condenser QJ between leads 51 and 52, thus essentially completely emptying condenser QJ of any charge remaining after the discharge thru tube FJ. Condenser QJ is now ready for recharging to time the next period from the same initial value, practically nil, from which the preceding period was timed.

In camshaft position 2 cam contact C22 is closed to energize the NS red signal RNS and cam contact C20 is closed, thus EW green signal GEW is energized. Timing in this period is achieved by the charging of condenser QJ by circuit from DC plus lead 55, cam contact C14, 45 adjustable resistance IEW, lead 52, condenser QJ to minus lead 51. As in position 1, when the potential across the condenser (which is also the potential across the tube FJ, since cam contact C8 is closed) reaches the threshold value for 50 conduction thru tube FJ, the latter becomes conducting operating relay J and solenoid S. Solenoid S advances the camshaft to position 3 and condenser QJ is discharged thru resistance RJ1 over solenoid contact S2 as before.

In position 3 there is no change in the signal indications, cam contacts C20 and C22 remaining operated in this period. This position may be called the EW vehicle interval position and its time duration is dependent upon traffic conditions at the intersection, as contrasted with positions 1 and 2 which were of predetermined length as set by the preadjusted resistances LNS and IEW. The operation in position 3 will now be considered under several possible traffic conditions.

Condition I for right of way on EW.—No traffic on the EW street and vehicle approaches on the NS street. Under this condition of traffic, that is, with no vehicle approaching on the EW street to which the right of way is being accorded, the condenser QJ is charged up by a circuit from DC positive lead 55 over cam contact C15, adjustable resistance VEW, lead 52 and condenser QJ to minus.

The vehicle approaching on the NS street actuates one of the detectors DNS which completes the circuit from lead 58 thru relay E, lead 64 and DNS to lead 51 energizing relay E. Relay E locks-in over its armature e_1 , lead 57 cam contact C18, (which is closed in all except position 6) lead 58 to minus lead 51. At armature e_2 relay E completes a yield or discharge circuit paralleling condenser QJ thru gas discharge tube FJ, relay J, lead 54, lead 66, back contact b_1 of relay BS, cam contact C17, lead 59, armature e_2 , to minus lead 51. Accordingly as soon as condenser QJ charges to the threshold conducting potential of tube FJ, relay J operates and in turn solenoid S operates to advance the cam shaft to the next position #4 to start to transfer right of way to the NS street.

Should the NS vehicle actuation not take place until after the voltage across condenser QJ has exceeded the threshold conducting potential of tube FJ, the latter will of course not become conducting until the actuation occurs and relay E closes the discharge circuit thru the tube as just traced via armature e_2 . If no NS actuation occurs this circuit remains open and the cam shaft remains in position 3 with right of way on EW.

Condition II for right of way on EW.—Vehicle waiting on NS street and light traffic (i. e. several vehicles) on EW street. Condenser QJ commences to be charged as in the above condition I over resistance VEW. Also as above the vehicle on the NS street actuates detector DNS and locks-in relay E which at armature e_2 connects the yield or discharge circuit thru discharge tube FJ, relay J and cam contact C17. Each vehicle on the EW street as it approaches the intersection actuates detector DEW, and each such actuation momentarily energizes relay D. Relay D 40 is not locked-in by these actuations since the lock-in circuit for relay D is open at cam contact C1 in position 3.

During each period of energization of relay D, which will be ordinarily inversely proportional to the speed of the actuating vehicle, armature d_2 completes a low resistance discharge circuit paralleling condenser QJ from leads 53, 52, resistance RJ2 cam contact C16, armature d_2 , to minus lead 51, thus reducing the charge on condenser QJ in accordance with the amount of charge on the condenser and the length of time this discharge circuit is completed. This feature is known as "speed variable reset" and the size of resistance RJ2 is arranged so that a vehicle crossing the detector just as tube FJ is about to become conducting will cause condenser QJ to be discharged sufficiently to give time for the vehicle to cross the intersection while the condenser voltage is again rising to the threshold potential of the tube. Each of the several vehicles, provided they are not spaced too far apart, will thus extend the EW right of way period in the manner described and after the last vehicle has crossed the intersection the condenser will have been recharged and tube FJ will operate, energizing relay J and solenoid S in turn in the manner described above to advance the cam shaft to position 4.

Condition III for right of way on EW.—Vehicle waiting on NS street and continuous traffic on EW street.

Under this condition of traffic at the intersection it will be appreciated from the preceding paragraph that the continuous traffic on the EW street will cause condenser QJ repeatedly to be

discharged over resistance RJ2. To prevent the possibility of such a continuous line of traffic from holding right of way indefinitely from vehicles waiting on the other street, a second condenser gas-discharge tube timing circuit is provided to serve as a maximum limit timer.

When relay E is locked-in as described above by the approach of a vehicle on the NS street, a circuit is completed at armature e3 to charge condenser QK. This circuit extends from D. C. positive lead 55 over resistance MEW back contact and armature as4 of relay AS, lead 60, cam contact C12, leads 61, 62, condenser QK, lead 67, armature bs2 and its back contact, armature as2 and its back contact, lead 63, cam contact C41, armature e3 to minus lead 51. In parallel with condenser QK, between leads 61 and 63, is a circuit including gas discharge tube FK and relay K. The tube FK is arranged to become conducting when the voltage across condenser QK has attained the threshold conducting value of tube FK and the current thru the tube will operate relay K. The period of the K timing circuit is arranged to be considerably greater than the period of the J timing circuit in the vehicle interval positions. It will be noted that cam contact 41 enables this maximum timing circuit to be active continuously thru positions 2 and 3 beginning with the arrival of a vehicle on NS causing closure of contact e3. Relay K at armature k1 completes the energization circuit for solenoid S from A. C. plus lead 50, lead 56, solenoid S, armature k1, to minus lead 51.

Further, operation of relay K causes the detector relay associated with the street from which right of way is being transferred to be energized and locked-in. At armature k2 a circuit from minus lead 51 is connected over dual contacts to energize both detector relays D and E. Relay E however has already been energized by DNS actuation and has been locked-in over its contact e1 so that the circuit over contact k2 for energizing relay E at this point now has no significance. Upon energization by contact k2 relay D is locked-in by a circuit from A. C. plus lead 50, relay D, armature d1, lead 65, armature s3 (while solenoid S is energized), back contact j2 (assumed closed), cam contact C18, lead 58 to minus lead 51, and after solenoid S is de-energized and has advanced the cam shaft into position 4 this lock-in circuit is completed over lead 65, cam contact C7, lead 58 to minus lead 51. It will be understood that solenoid S is arranged to so shift the cam shaft only during its movement returning to normal from its energized position. Thus when the right of way is forcibly removed from a street by the maximum timer, armature k2 operates with armature s3 and serves to lock-in the detector relay of the street from which right of way is being removed in order that vehicles stopped by such a transfer without sufficient time to clear the intersection after actuating the detector may be permitted to proceed by the recall of right of way to that street at the earliest opportunity consistent with traffic on the other street but at the longest within the maximum period for the other street.

If both condensers QJ and QK should reach the conducting potentials of their respective discharge tubes FJ and FK simultaneously, both relays J and K would be operated, and since under these conditions relay J has been operated indicating that sufficient time has elapsed for the last actuating vehicle on the EW street to cross the intersection, relay D should not be

locked-in since no vehicle will have been forced to stop. Accordingly although relay K operates armature k2, the locking-in circuit over armatures j2 and s3 is not completed since relay J operates and opens the circuit at armature j2, and consequently relay D will not be locked-in under this condition.

Relay K, when operated, at armature k3 completes the circuit thru tube FJ and relay J shunting condenser QJ, but this has no significance here since a corresponding circuit has already been completed via contact e2 and cam C17 and the purpose of this circuit will be subsequently explained.

On any shift of the cam shaft from positions 3 or 6 the solenoid S completes at armature s1 a discharge circuit for condenser QK over leads 62, 61, cam contact C31, armature s1, resistance RK1, lead 67, condenser QK. Thus condenser QK will be prepared to commence its next timing interval from a discharged condition. At armature s2 condenser QJ is similarly discharged in the manner aforescribed.

In position 4 of the cam shaft cam contacts C22 and C16 are operative to energize the NS red signal RNS and the EW yellow, YEW. Condenser QJ is charged by a circuit from D. C. positive lead 55 cam contacts C2, adjustable resistance LEW, leads 52 and 53, and when the potential of the condenser has reached the threshold conducting potential of tube FJ, the tube becomes conducting, operating relay J and in turn solenoid S to advance the cam shaft in the manner previously described to position 5, the NS initial position.

Cam contacts C9 and C11 are now closed energizing respectively the NS green signal GNS and the EW red signal REW. A charging circuit for condenser QJ is completed over adjustable resistance INS and cam contact C3 to charge condenser QJ to the threshold conducting potential of tube FJ which operates in the aforescribed manner and the cam shaft advances to the NS vehicle interval position 6.

In position 6 the signal indications remain as they were in position 5. The duration of this period is also dependent upon traffic conditions at the intersection and the operation of the controller is similar to the operation described for position 3 excepting that now right of way is on the NS street instead of the EW street and the effects of traffic actuation on the two streets are now interchanged. It is believed that with the summary presented below concerning operation under three conditions of traffic such operation will be readily understood in view of the complete description presented in connection with position 3.

Condition I for right of way on NS.—No traffic on NS street and vehicle approaches on EW street.

The vehicle approaching on the EW street actuates detector DEW and relay D which is locked-in over armature d1, cam contact C7 and lead 58 to minus lead 51. At armature d2 relay D completes the yield or discharge circuit for condenser QJ thru gas discharge tube FJ, relay J, lead 54, lead 66, back contact and armature as1 of relay AS cam contact C6, contact d2 to minus lead 51. As soon as the potential on condenser QJ reaches the threshold conducting voltage of tube FJ relay J operates to advance the cam shaft to position 1.

Condition II for right of way on NS.—Vehicle waiting on EW street, light traffic (i. e. several vehicles) on NS street.

In this condition condenser QJ, which is being charged meanwhile over adjustable resistance VNS and cam contact C4, is reset by vehicles approaching on the NS street to hold right of way from being transferred to street EW. Each actuation of detector DNS and consequent energization of relay E, at armature e2 completes a low resistance discharge circuit for condenser QJ from leads 53, 52, resistance RJ3, cam contact C5, lead 58, armature e2, to minus lead 51. The charge on condenser QJ will an appropriate time after the last NS vehicle has actuated detector DNS reach the critical potential of tube FJ and operate relay J to cause shift on the cam shaft from position 6.

Condition III for right of way on NS.—Vehicle waiting on EW street, continuous traffic on NS street.

As in Condition II, the charge on condenser QJ which is being increased by the charging thru resistance VNS is subjected to resetting by vehicles actuating detector DNS in the street having right of way. If the traffic flow is substantially continuous the voltage across condenser QJ will not reach the critical potential of tube FJ due to the continued resetting via resistance RJ3. The maximum timing circuit, which becomes operative upon actuation on the opposing street, street EW, is effective meanwhile, and condenser QK is charged by circuit from lead 55 over resistance MNS, back contact and armature bs4 of relay BS, cam contact C1, leads 61 and 62, lead 67, back contact bs2 of relay BS, back contact as2 of relay AS, cam contact C30, contact d3 of relay D to minus lead 51. When the voltage on condenser QK reaches the critical potential of tube FK, the latter becomes conducting and relay K is operated. In turn over armature k1 solenoid S is operated to advance the cam shaft to position 1 and thus initiate transfer of right of way from the NS to the EW street.

A complete cycle of operation has now been described. It will be seen when the local controller is operating independently, that is, when both supervisory relays AS and BS are de-energized that right of way will remain on one street in the absence of traffic actuation on the other street; that right of way will, after the expiration of a minimum or initial period, be transferred immediately to the other street in response to traffic actuation on the latter street, but traffic on the street possessing right of way may postpone such transfer up to a predetermined maximum time.

Connection II.—Arterial on recall switch HNS closed and switch HEW open.

With recall switch HNS closed, it will be seen that in all camshaft positions except NS vehicle interval position 6 a circuit will be completed from plus lead 50 thru relay E, lead 64, lead 68, switch HNS, lead 57, cam contact C18 and lead 58 to minus lead 51. Thus relay E will be energized in all except position 6. The effect of such operation will be to place an artificial "call" or traffic actuation on the NS street whenever right of way is not accorded thereto so that right of way will be returned thereto automatically after any gap in EW traffic during position 3 sufficient to permit the condenser to charge up and operate the tube FJ, or after the EW maximum interval if no gap appears in the EW traffic.

Since the circuit thru switch HNS is open at cam contact C18 in the NS vehicle interval position 6 the relay E is energized in this position only upon actuation of one of the detectors DNS,

and the switch HNS thus has no holding effect on NS right of way.

Thus with connection II right of way reverts automatically to NS or A street and in the absence of traffic on EW or B street right of way remains on A street.

Connection III.—Arterial or recall switch HEW closed and switch HNS open.

With recall switch HEW closed, a circuit is completed via cam contact C7 to energize relay D in all positions except #3 the EW vehicle interval position. Thus this switch serves to cause automatic recall of right of way to EW in the same fashion as switch HNS causes recall of right of way to NS as described above under Connection II.

With Connection III right of way reverts automatically to B street and remains there normally in the absence of traffic on A street.

Connection IV.—Both recall switches NHS and HEW closed.

With both switches HNS and HEW closed relay D is energized in all positions except #3 and relay E is energized in all positions except #6 so that the right of way is recalled automatically to each street from the other and in the absence of traffic on both streets the right of way reverts back and forth at minimum intervals including one initial interval, one vehicle interval, and one yellow interval on each street. Traffic on NS during the NS right of way period is able to prolong the right of way period up to the NS maximum, and traffic on EW during the EW right of way period is able to prolong the right of way period up to the EW maximum.

Having now described the operation of the full traffic actuated local controller as independent of supervisory control, the operation of the same under the control of the supervisory relays and master controller in accordance with the invention will now be described.

At the upper left side of Fig. 5 the portion of the master controller of Fig. 1 associated with the intersection of A street and B street is repeated to aid in tracing the operation of the supervisory control on the local controller of Fig. 5. It will be appreciated that the cyclic contact devices MB1 and MB2 may be either located at a central point and operated cyclically by the motor M in common with the corresponding contact devices for the other intersections as shown in Fig. 1, or these devices may be located at the respective intersections and driven by separate motors, employing motors of the synchronous type or synchronized with each other by any of the well known methods at each intersection.

The master controller contacts MB1 and MB2 are connected to supervisory relays AS and BS respectively, the latter relays being shown on the lower left side of Fig. 5. The switches SAS and SBS are provided to permit either or both of these relays to be disconnected and may be operated locally or by remote control by means of an auxiliary electromagnet not shown for example in accordance with well known practice.

The supervisory relays each have a number of contacts connected to the local controller to provide control of the transfer of right of way by the latter, particularly from cam shaft positions 3 and 6 the vehicle interval green signal positions for the respective streets B and A.

The contact devices MB1 and MB2 are arranged in proper time phase relation with the corresponding master control contacts for the

other intersections in accordance with the co-ordination plan whether for preferred simultaneous transfer of right of way at all intersections or for progressive transfer for progressive traffic movement along A street for example. In Fig. 1 and in the related showings of the master control contact devices in Figs. 5, 6, and 7 the contact closure periods are shown in spaced phase relation as they might be arranged for progressive movement along A street for example, it being assumed for ease of comparison between the full actuated and semi-actuated operations illustrated at A street-B street intersection and A street-C street intersection respectively that the preferred transfer points in the background cycle are in phase, with A street portion of the background cycle about 65% of the total and the B street and C street portions of the cycle about 35%. It will be understood that these figures are used for illustration only and that the contact periods can be arranged for any proportion of the cycle and any phase relation desired. The 35%-65% division of the background or supervisory cycle thus assumed for Fig. 5 and Fig. 6 conforms approximately with the corresponding cycle diagrams in Fig. 3 and Fig. 4.

Considering now Fig. 5 in relation to Fig. 3 the top of the contact discs MB1 and MB2 in the position shown in Fig. 5 corresponds with point O on the cycle diagram of Fig. 3 as the preferred point for transfer of right of way to N—S or A street, and the portion of these discs approximately 240 degrees of arc clockwise around the circle corresponds with point T on the cycle diagram.

It will be seen that the unshaded or conducting portion of the contact disc MB1 extends some distance on either side of the top and this corresponds with the A street preparatory period of Fig. 3 to the left of the top and extending thru the A street right of way guarantee period to the right of the top. Thus assuming switches MCS, SAS and SBS closed, as is the case for supervisory control operation, as the two discs MB1 and MB2 rotate in phase the relay AS is first energized by contact MB1 for a portion of the master control cycle and then de-energized, and later relay BS is energized for another portion of the cycle and de-energized, these portions of the cycle corresponding with portions AP to AG and BP to BG respectively of the cycle diagram of Fig. 3.

The actual effects of such periodic energization of relays AS and BS on the transfer of right of way depend on which position of the cam shaft the local traffic actuated controller is in and the presence or absence of traffic on the streets as recorded by actuation of the detectors DNS and DEW.

If either relay AS or BS is energized during one of the yellow signal periods with the local controller on position 1 or position 4 for example, the local controller proceeds with normal timing of this period and shifts to the next position without interference from the supervisory control.

Also in the initial interval positions 2 and 5 of the local controller the energization of either relay AS or BS does not restrict the normal time of these intervals, and although the proper preparatory interval timing is initiated by these relays in this position as will be subsequently described, the controller shifts from either initial interval position to the next without restriction.

In the vehicle interval positions however the 75

relays AS and BS have certain restrictive effects corresponding to the supervisory control functions described in connection with Fig. 3. If relay AS is energized while the local controller is on the NS vehicle interval position 6 with right of way on A street for example, the local controller is prevented from shifting from this position and thus the transfer of right of way from A street is prevented. If relay AS is energized while the local controller is in the EW vehicle interval position 3 with right of way on EW, the shift of the camshaft from position 3 can occur in the normal manner by the operation of relay J through tube FJ by condenser QJ as aforescribed under "Condition I" or "Condition II" for "Connection I" during the first part of the energization period of relay AS. During this part of that period however the normal timing action of the condenser QK as a maximum timer is interrupted by relay AS, and condenser QK and its associated tube FK and relay K are employed to time a period corresponding substantially with the A street preparatory period of Fig. 3, at the end of which period and thereafter until relay AS is again de-energized the shift of the cam shaft from position 3 is caused immediately upon energization of relay E by actuation of the detector DNS if such shift has not already occurred normally by operation of the J relay as above. This action causes a forced transfer of right of way from B street. The circuits for causing this action will be subsequently described.

Similarly if relay BS is energized in the EW vehicle interval position 3 with right of way on B street the shift of the cam shaft from this position will be prevented, and if this relay is energized in the NS vehicle interval position 6 of the cam shaft, after a preparatory period timed by condenser QK the shift of the cam shaft from this position is forced immediately upon energization of relay D. The time periods of condenser QK upon energization of relays AS and BS are preferably adjusted to be a few seconds shorter than the actual preparatory period of the background cycle as determined by the setting of the MB1 and MB2 contact periods in order to allow for the yellow signal intervals. For instance if the yellow interval following B street green is 3 seconds and the A street preparatory period of the background cycle is 18 seconds the adjusting resistance APNS is preferably set to give a 15 second period for charging condenser QK during the first part of the time relay AS is energized.

The circuits for the several functions of the AS and BS relays as aforescribed will now be traced. First assuming relay AS to be energized and the local controller to be in cam shaft position 6 the NS vehicle interval position, it will be seen that right of way is on A street. In this position by reference to the operation in "Condition I" and "Condition II" for right of way on NS under Connection I aforescribed it will be observed that the circuit for operation of tube FJ and relay J by condenser QJ through closure of contact d2 of relay D includes the back contact as1 and thus the opening of the contact as1 by energization of relay AS opens this circuit and thus prevents energization of relay J. Also at contact as5 which is now closed, a circuit is completed to maintain the condenser QK discharged and thus prevent the operation of tube FK and relay K. This circuit may be traced from the right side of QK via lead 62, lead 61, cam contact C1, lead 69,

contact *as5*, low resistance *RK3*, lead *67* to the left side of *QK*.

Since both relays *J* and *K* are thus prevented from operating, the energization of solenoid *S* and the consequent transfer of right of way from *A* street is prevented, while relay *AS* is energized.

When relay *AS* is first energized the make-break contact *as3* momentarily closes a circuit for discharging condenser *QK* in order to prepare the condenser for being recharged to time an auxiliary interval corresponding to the *A* street preparatory interval. This circuit extends from the right side of *QK* via lead *62*, low resistance *RK2*, contact *as3*, lead *61* to the left side of *QK*. The circuit through contact *as3* remains open in the completely energized position and in the completely de-energized position of relay *AS* but is closed momentarily upon initial energization or initial de-energization of the relay.

Also when relay *AS* is energized a circuit is completed for charging condenser *QK* to time the auxiliary interval corresponding to the *A* street preparatory interval if the right of way is on *B* street, i. e. if the local controller is in position 2 or 3. This circuit extends from D. C. positive lead *55*, time adjusting resistance *APNS*, lead *70*, contact *as4*, lead *60*, cam *C12*, lead *61*, lead *62*, *QK*, lead *67*, back contact *bs2*, front contact *as2* to minus lead *51*.

Condenser *QK* will thus charge up and after an interval dependent upon the setting of adjusting resistance *APNS* the voltage across the condenser will reach the threshold conducting value of tube *FK*. The end of this time period corresponds substantially with point *O* on the cycle diagram of Fig. 3, with allowance for the *YEW* clearance interval.

The circuit operation of relay *K* through tube *FK* from the charge on condenser *QK* will not be completed however unless or until the relay *E* is energized to close contact *e3*, assuming that switch *TNS*, the function of which will later be described, is open. This circuit via relay *K* is closed when *e3* is closed and extends from the right side of *QK*, lead *62*, lead *61*, tube *FK*, relay *K*, lead *63*, cam *C41*, contact *e3*, to minus lead *51*, which is connected via make contact *as2*, back contact *bs2*, lead *67* to the left side of *QK*.

Thus as soon as relay *E* is energized by traffic on *A* street the condenser *QK* will discharge thru tube *FK* and relay *K* and cause shift of the cam shaft from position 3 resulting in transfer of right of way, after the yellow interval, to *A* street. It will be noted that, as in the case of this condenser *QK* serving as a maximum timer in the normal fashion, the operation of relay *K* causes the shift from position 3 irrespective of traffic on *B* street and therefore causes at contact *k2* energization and lock-in of relay *D*, if relay *J* is not operated simultaneously, so as to cause right of way to return later to *B* street to care for traffic thus interrupted by transfer of right of way from *B* street.

Thus with switch *TNS* open the relay *AS* in cooperation with the condenser *QK* and charging resistance *APNS* serves to force upon *A* street actuation the immediate the transfer of right of way to *A* street at the point *O* and thereafter during the *A* street right of way guarantee period of the supervisory cycle.

If it is desired to cause transfer of right of way to *A* street at point *O* (if transfer has not already occurred) even in the absence of traf-

fic actuation on *A* street in order to care for pedestrians, or to prepare for the expected progressive wave of vehicles, or other reason, the switch *TNS* is closed and the circuit for operation of relay *K* by the discharge of condenser *QK* through tube *FK* is thereby completed via *TNS* and make contact *as6* to negative lead *51* thus shunting the contact *e3* on relay *E* and causing operation of the solenoid by relay *K* even in the absence of actuation of *DNS*.

Under this condition contact *k3* completes the operating circuit for relay *J* from condenser *QJ* so that if relay *J* has been charged to the threshold potential of tube *FJ* thus indicating that sufficient time has elapsed after the last actuation for all *EW* vehicles to clear the intersection, relay *J* will be operated and at its contact *j2* will prevent the locking-in of relay *D* and consequently prevent unnecessary recall of right of way to the *EW* street. If condenser *QJ* is not so charged sufficiently, however, tube *FJ* will not be rendered conducting and closure of contact *k3* will not energize relay *J*. Consequently relay *D* will be locked-in as contact *j2* will remain closed. The time and order of operation of the contacts on relays *J* and *K* are arranged so that contact *j2* remains open until after *k2* has opened on de-energization of relay *K* if both of these relays are operated simultaneously.

Considering now the effects of operation of supervisory relay *BS* it is noted that this relay is energized during the closed contact period of master control contact *MB2*, which corresponds with the period *BP* to *BG* in the supervisory cycle diagram of Fig. 3. It will be seen that contact *MB1* is thus open and relay *AS* de-energized at that time.

Relay *BS* has the same functions with respect to preventing transfer from and forcing transfer to *B* street as relay *AS* has for *A* street as described above. The transfer of right of way from *B* street is prevented by the opening at back contact *bs1* of the relay *J* operating circuit via contact *e2* of the relay *E*, so that the solenoid *S* will not be operated by contact *j1* in the *EW* vehicle interval position 3. Also at front contact *bs5* the condenser *QK* is kept discharged in position 3 by a circuit from the right side of *QK* via lead *62*, lead *61*, cam contact *C12*, contact *bs5*, low resistance *RK5*, lead *61*, to the left side of *QK*. This prevents *QK* from being charged and thus relay *K* cannot be energized to operate solenoid *S*. Consequently solenoid *S* cannot be operated in position 3 with the *BS* relay energized and right of way is held on *B* street.

If the cam shaft is in position 5 or 6 when relay *BS* is energized a charging circuit for condenser *QK* is completed via adjusting resistance *BPEW* and make contact *bs4* to time a preparatory interval for *B* street corresponding substantially with the *B* street preparatory interval *BP* to *T* on the cycle diagram of Fig. 3. This circuit extends from D. C. positive *55* via resistance *BPEW* lead *71*, make contact *bs4*, lead *69*, cam *C1*, lead *61*, lead *62*, *QK*, lead *67*, front contact *bs2* and minus lead *51*.

At the initial energization of relay *BS* a momentary discharge circuit for condenser *QK* is completed over the momentary make-break contact *bs3* from the right side of *QK*, via lead *62*, lead *61*, low resistance *RK4*, momentary make-break contact *bs3*, lead *67* to left side of *QK*. This momentary discharge prepares the con-

denser QK for timing the B street preparatory interval. This circuit is also completed momentarily on de-energization of relay BS to discharge QK so that the forced transfer effect will not carry into the BG-AP period.

After the preparatory interval for B street, timed by condenser QK in co-operation with resistance BPEW and contact bs4, condenser QK is charged to the threshold voltage of tube FK and for a period corresponding to the T-BG portion of the cycle diagram of Fig. 3, the shift of the local controller from position 6 is caused immediately by operation of tube FK and relay K and consequently solenoid S, if or as soon as relay D is energized closing contact d3 (assuming switch TEW open), thus forcing the transfer of right of way to B street if any traffic is on B street.

This circuit for operating relay K extends from QK via lead 62, lead 61, tube FK, relay K, lead 63, cam contact C30, contact d3, negative lead 51, which via contact bs2, lead 61 is connected to the other side of condenser QK. If there is no traffic on B street relay D will remain de-energized and relay K will not be operated to shift from position 6 will not occur and right of way will remain on A street.

It will be appreciated that during the preparatory interval for B street the shift from position 6 can occur in normal fashion as aforescribed under "Condition I" and "Condition II" for right of way on A street by operation of the relay J if relay D is operated by traffic on B street and there is no traffic actuation on A street for a sufficient time to permit condenser QJ to charge to the threshold voltage of tube FJ.

Switch TEW, which was assumed open in the above description, can be closed if desired to cause automatic shift from position 6 at point T even if relay D remains de-energized as in the absence of traffic on B street. This is accomplished by a circuit shunting contact d3 via make contact bs6 and switch TEW to negative lead 51.

In any case of operation of relay K to cause a forced shift from position 6 the relay E is energized over contact k2 in case relay J is not energized at that time so as to recall right of way to A street for the protection of traffic that may be interrupted as aforescribed in the case of corresponding interruption of traffic on B street by forced shift from position 3.

It will be noted by reference to the contact discs MB1 and MB2 that supervisory relay AS is energized only during the "preparatory" period for A street and the "guarantee" period for B street, and that supervisory relay BS is energized only during the "preparatory" and "guarantee" periods for B street, both relays being de-energized for the two intervening periods. During these intervening periods corresponding with period AG to BP and period BG to AP in the cycle diagram of Fig. 3 therefore the local controller is free from supervisory control and the operation of the local controlled is independent as first described with both relays AS and BS de-energized, the transfer of right of way after the normal minimum periods then being dependent solely on traffic actuation.

Thus it will be seen that by means of the supervisory relays in co-operation with master control contacts MB1 and MB2 the transfer of right of way by the local traffic actuated controller is cyclically controlled so as to favor the according of right of way first to one street in

its preferred portion of the master control supervisory cycle and then to the other street in its preferred portion of the cycle.

At the beginning of the preferred right of way portion of the cycle for one street right of way transfer to that street is preferably forced immediately in event of actuation on that street if right of way has not already been transferred to that street. At that time and for a short period before the end of the preferred right of way portion of the cycle for the other street the transfer of right of way from said one street to said other street is prevented if the right of way is already accorded to said one street. In intervening portions of the cycle with right of way on either street the transfer of right of way is governed preferably by traffic actuation independently of the supervisory control.

Now referring to Fig. 6 in connection with Fig. 4 the operation of the one form of supervisory control over a semi-traffic actuated local controller will be described.

It will be recalled that in the description of Fig. 4 it was pointed out that traffic detectors are located only in the C street or EW and the right of way remains normally on the A street or NS in the absence of actuation on C street, the right of way being transferred to C street in the event of actuation there and after a period variable by further actuation between a minimum and a maximum the right of way is retransferred automatically to A street.

This form of operation is accomplished simply by closing switch HNS and properly adjusting the initial interval and vehicle interval resistances INS and VNS to provide a proper protective minimum period for A street traffic.

In Fig. 6 the local controller is shown of the same construction as that of Fig. 5 except that with the omission of supervisory relay BS which is not required in semi-actuated operation the circuits ordinarily passing through the back contacts of relay BS now are completed directly in Fig. 6 with the same effect as having these back contacts of relay BS permanently closed in Fig. 5. In addition the B street preparatory timing interval is not needed and the adjusting resistance BPEW of Fig. 5 for this interval is omitted in Fig. 6. Also the switch TNS and associated contact as6 of relay AS of Fig. 5 is not needed in semi-actuated operation as relay E is always energized in position 3 of the cam shaft where switch TNS would only be effective if relay E were de-energized.

With these minor changes the circuits and fundamentals of operation of the local controller in Fig. 6 are the same as already described for full actuated operation and need not be repeated, it being noted however that in the semi-actuated type of operation as in Fig. 6 the relay E remains energized in all positions except the NS or A street vehicle interval position 6 as described in Connection II, and to aid in visualizing the semi-actuated operation this relay E is shown energized in Fig. 6 as in any of positions 1 thru 5 inclusive.

If relay AS is assumed to be de-energized continuously as in the case of switch SAS being in the open position, the local controller is independent of any supervisory control and acts as an individual semi-traffic actuated controller.

There are a few main differences to be noted in the semi-actuated operation from the full

actuated operation. The maximum timing actuation via MNS resistance for limiting A street right of way is not needed and is therefore normally set longer than the desired A street right of way period, and the latter is determined by the total of the initial interval plus the vehicle interval for A street as determined by the adjusting resistance INS and VNS. The relay E being de-energized in position 6 the condenser QJ continues to be charged without discharging action up to the threshold voltage of tube FJ, at which point the relay J operates to initiate transfer of right of way to B street on any B street traffic actuation of DEW and consequent energization of relay D, assuming that relay AS is de-energized and contact *as1* closed. If D is not operated the condenser continues to charge above the threshold value to line voltage and the local controller rests on position 6 with right of way on A street.

In addition it will be appreciated that in independent semi-actuated operation the timing of the maximum period for the cross street C or EW right of way is started with the charging of condenser QK at the beginning of the EW initial interval in position 2 when cam contact C12 closes since contact *e3* of relay E is closed in this position. It will be further noted that with relay E always energized in the EW vehicle interval, position 3 the condenser QJ operates relay J via tube FJ and causes the solenoid S to initiate transfer of right of way from C street as soon as there is a sufficient gap in EW or C street traffic to permit the condenser QJ to reach the threshold voltage of tube FJ.

With the above briefly described differences in mind the supervisory control operation will now be described for Fig. 6 in connection with the corresponding supervisory cycle diagram in Fig. 4.

Only one master control contact device MC1 is now required and this is arranged to close and maintain relay AS operated for a period corresponding with the AP to T (clockwise) portion of the supervisory cycle diagram of Fig. 4. This entire period serves as a preventive period for transfer of right of way from A street, the remainder of the cycle from T to AP serves as a permissive period for transfer of right of way to C street if traffic actuation on C street occurs or has previously occurred since the last previous right of way period for C street.

This preventing of transfer of right of way from A street occurs through energization of relay AS and consequent interruption of the relay J operating circuit in position 6 of the cam shaft just as afore-described for full actuated operation.

Correspondingly the energization of relay AS serves in cooperation with adjusting resistance APNS to employ the condenser QK, to time the A street preparatory interval by charging condenser QK over a circuit from D. C. positive lead 55, resistance APNS, lead 10, contact *as4*, lead 60, cam contact C12, leads 61, 62, condenser QK, lead 67, make contact *as2* to minus lead 51, which corresponds to a similar circuit previously described for full actuated operation. If right of way is on C street during this interval it is transferred to A street upon any gap in C street traffic sufficient to permit condenser QJ to be charged to operate relay J. If there is no gap in C street traffic however the transfer of right of way to A street is forced at point O of the cycle diagram thru action of condenser QK in operat-

ing relay K as previously described, the supervisory control thus serving as an automatic maximum limit to right of way on C street.

During the C street permissive period, i. e. when relay AS is de-energized, transfer of right of way from A street occurs on any C street traffic actuation previously recorded or if there is none such then at the first C street actuation occurring during the permissive period.

10 The local controller could of course be arranged to provide only a predetermined time period of right of way to C street not subject to variation by actuation simply by omitting RJ2 and having an open circuit at this point, but preferably it is arranged as shown.

An alternative form of supervisory control employing essentially the same fundamental principles and using the same type of full actuated controller as in Fig. 5 is shown in Fig. 7. In this 20 case however in lieu of using only the master control contact devices MB1 and MB2 and employing the condenser QK timing circuit to time the preparatory intervals in cooperation with relays AS and BS, these periods are cared for by 25 providing two additional contact devices MB3 and MB4 to operate added supervisory relays AST and BST respectively.

The relays AS and BS of Fig. 7 are arranged to be energized throughout the periods AP to AG 30 and BP to BG respectively in the supervisory cycle of Fig. 3 as in Fig. 5, and these relays retain their function of preventing transfer from the respective streets A and B as before described. Contacts *as1* and *bs1* when open prevent the operation of relay J in position 6 and position 3

35 respectively, and the contacts *as5* and *bs5* when closed prevent charging of condenser QK and consequently prevent operation of relay K in these respective positions, all as aforescribed in

40 connection with Fig. 5. The armatures *as2*, *as3*, and *as4* are omitted as well as corresponding armatures *bs2*, *bs3*, and *bs4* as unnecessary in Fig. 7 and the circuits passing through the back contacts associated with these armatures are permanently completed directly.

45 The function of forcing transfer of right of way in the proper portions of the background cycle is performed by supervisory relays AST and BST of Fig. 5 in co-operation with master control contacts MB3 and MB4. The latter are arranged to energize relays AST and BST throughout the O to AG and T to BG portions of the supervisory cycle, respectively corresponding to the right of way guarantee periods.

The relay AST, energized at point O serves to 55 force the transfer of right of way to A street on any traffic actuation on that street if such transfer has not already occurred, and if no such actuation has occurred at that point it maintains the local controller in readiness to transfer right of way immediately to A street upon the first actuation there during the A street right of way guarantee period, assuming that switch TNS is open as shown. This function is accomplished thru the closing of make contact *ast3* which places a shunt thru relatively low resistance RK6 across the normal EW maximum time adjusting resistance MEW so as to charge substantially immediately condenser QK to or above the threshold voltage of tube FK regardless of what the normal time setting for the EW maximum period is.

70 Although this shunting circuit across resistance MEW is effective to charge the condenser QK quickly in positions 2 and 3 of the cam shaft

through cam C12 this does not reduce the period in the initial interval position to a very small value since the relation of the time of operation of relays AST and AS and the timing of the initial interval is such that thru the action of relay AS in preventing transfer of right of way from A street after point AP the local controller if giving right of way to B street just before point O must have already passed thru the initial interval.

This rapid charging of condenser QK by relay AST via contact ast3 prepares the condenser QK for its immediate operation of relay K upon closure of the relay K operating circuit at contact e3 of relay E as already described for Fig. 5 and thus cause shift from position 3 and transfer of right of way from B street. If or as soon as traffic actuation occurs on A street and relay E is energized the transfer of right of way to A street is forced immediately if such transfer has not already occurred.

If the right of way is still on B street at point AG of the cycle on account of absence of actuation on A street, the de-energization of relay AST at this point will at its momentary make-break contact ast2 discharge condenser QK over low resistance RK2 so A street actuations during the AG-BP period will not force transfer to A street, assuming proper adjustment of contacts ast2 and ast3.

As aforementioned this action assumes that switch TNS is open. If it is desired to have automatic transfer at point O in the supervisory cycle the switch TNS is closed and the relay AST then over make contact ast1 and switch TNS shunts the contact e3 and completes the operating circuit for the relay K from the condenser QK irrespective of the condition of relay E.

The relay BST, energized at point T in the supervisory cycle, serves to force transfer of right of way to B street on B street actuation if such transfer has not already occurred. This is accomplished by shunting the normal maximum timing resistance MNS with relatively low resistance RK6 via make contact bst3, thus causing quick charging of condenser QK in the NS vehicle interval position 6 over cam C1 in the same fashion as previously described for relay AST in position 3.

With condenser QK charged the shift from position 6 is caused (assuming switch TEW open) as soon as relay D is operated to close through contact d3 the operating circuit of relay K. If no traffic actuation on B street has yet occurred the condenser QK remains charged and the shift from position 6 occurs immediately upon the first actuation to occur on B street during the B street right of way guaranteed period.

At the moment of de-energization of relay BST at point BG the condenser QK is discharged over contact bst2 and low resistance RK4, so as to discontinue the forced transfer effect.

If it is desired to have automatic transfer of right of way to B street at point T irrespective of traffic actuation, the switch TEW is closed, and then energization of relay BST will at make contact bst1 and via switch TEW shunt contact d3 of relay D, thus rendering the circuit for operating relay K from condenser QK independent of the condition of relay D.

It will be understood that the contact periods of relays AST and BST could if desired by properly arranging the segments of contact discs MB3 and MB4 be made to extend beyond the point AG and BG respectively even though relays AS

and BS are de-energized at these points. The effect would then be that transfer of right of way to A street for example would be forced by any A street actuation occurring while right of way is on B street even though the right of way holding effect on A street by relay AS had ceased. This effect could be continued until just before point BP in the cycle if desired. Correspondingly similar forced transfer to B might be provided for from point T until just before point AT.

It will also be readily appreciated that the apparatus of Fig. 7 could be arranged for semi-actuated operation by closure of switch HNS by properly setting the time adjusting resistances 15 as previously outlined in connection with Fig. 6. The relays BS and BST could be retained de-energized by opening of switches SBS and SBT for semi-actuated operation, or as in Fig. 6 these relays could be omitted and the circuits now 20 shown through their back contacts permanently completed as if the contacts were always closed. In the latter case only master control contacts MB1 and MB3 would be required.

It will be further appreciated that the apparatus of Fig. 6, with the EW detectors DEW omitted, the switch HEW closed as well as switch HNS, and the adjusting resistances IEW and VEW properly set to provide a sum of the initial 25 and vehicle intervals of slightly greater than the EW (or C street or Z street) portion of the supervisory cycle, the local controller will serve as a fixed time or non-traffic actuated control system and as a part of the entire co-ordinated system, as indicated at the intersection of A and Z streets in Fig. 1. In this case the automatic transfer of right of way to A street will always occur at point O of the supervisory cycle, in spite of the uncompletion of the QJ condenser time period, thru action of relay AS, and the right of way will always be transferred at point T of the supervisory cycle to Z street, at de-energization 40 of relay AS, since relay D will be energized at this time thru switch HEW. Thus for fixed time operation only one master control contact 45 and one supervisory relay is required.

It will thus be seen that in accordance with the invention a very flexible type of co-ordinated traffic control system is provided by means of which individual traffic actuated signal systems 50 at one or more intersections can be supervised in relation to each other or in relation to non-traffic actuated systems to favor traffic movement through the group of intersections in accordance with a predetermined progressive or other plan, and yet provide for variation from that plan to better serve traffic at the individual intersections when such traffic varies from the predetermined plan, such variation from the plan being arranged to have a minimum of interference with traffic moving thru the several intersections in accordance with such plan.

It will be appreciated by those skilled in the art that although contacts MB1, MB2, etc. are shown closed to energize relays AS and BS respectively during the periods AP to AG and BP to BG respectively, the conducting and non-conducting segments could be interchanged and the relays AS and BS could have their make contacts generally interchanged with their break contacts except in the case of contacts as3 and bs3 so that these relays would perform their preventive function etc. when de-energized instead of when energized as shown. These relays and master control contacts are preferably arranged 70 as shown however so that in the event of failure 75

of power on the master control circuits both relays AS and BS will be automatically de-energized and the local controller will operate independently.

It will be understood that the above description and accompanying drawings are illustrative only, that the invention is capable of use in a wide variety of conditions and in many forms, of which a few alternate arrangements are shown herein for purposes of exemplification, and that various modifications in the structural details or arrangements of the parts, or changes in the designs shown may be made without departing from the spirit of the invention as defined by the claims.

I claim:

1. In a traffic control system for the intersection of two interfering traffic lanes including a first traffic lane and a second traffic lane, signalling means to accord and interrupt right of way in the lanes, traffic actuated means in the lanes, and a cyclic signal switching mechanism having a plurality of positions through which it is adapted to be operated, including at least one position for accord of right of way to said first lane and another position for according right of way to said second lane, a minimum timer device connected with said mechanism to be energized by the latter in each one of said first and second positions to maintain said mechanism in one position according right of way to the one lane for at least a minimum period and connected normally to condition said mechanism at the end of such minimum period for transfer to the other position to transfer right of way to the other lane in response to actuation of the traffic actuated means in such other lane, means including a connection with said mechanism in said first position and the traffic actuated means of said first lane to interrupt the normal timing operation of said timer device momentarily by actuation in said first lane to postpone such conditioning so as to prolong right of way on said first lane beyond said minimum and means including a connection with said mechanism in said second position and the traffic actuated means of said second lane to interrupt the normal timing operation of said timer device momentarily by actuation in said second lane to postpone such conditioning so as to prolong right of way on said second lane beyond said minimum, a supervisory switch device operating in continuously repeated time cycles of length much greater than said minimum period in a first part of which cycle right of way is preferred to said first lane and in a second part of which cycle right of way is preferred to said second lane and in intervening parts of which cycle there is no preference for either lane, said supervisory device including switching means operating in said first part of such cycle to interrupt such conditioning of said mechanism by said minimum timer in said first position so as to prevent transfer of right of way from said first lane in said first part of such cycle if said mechanism is in said first position according right of way to said first lane, said supervisory device also including switching means operating in said second part of such cycle and connected to said mechanism to interrupt such conditioning by said minimum timer in said second position so as to prevent transfer of right of way from said second lane in said second part of such cycle if said mechanism is in said second position according

right of way to said second lane, said supervisory device also including switching means operated in at least a portion of said first part of said cycle for connecting the traffic actuated means of said first lane to said mechanism in said second position directly to transfer said mechanism to its first position immediately in response to actuation on said first lane to force transfer of right of way to said first lane if said mechanism is then in said second position according right of way to said second lane, and said supervisory device also including switching means operated in at least a portion of said second part of said cycle for connecting the traffic actuated means of said second lane to said mechanism in said first position directly to transfer said mechanism to its second position immediately in response to actuation on said second lane to force transfer of right of way to said second lane if said mechanism is then in said first position according right of way to said first lane.

2. A traffic control system for the intersection of interfering traffic lanes including signalling means adapted to accord right of way successively to the lanes, traffic actuated means in one of the lanes, a control mechanism to operate said signalling means to transfer right of way to said one lane from another lane in response to actuation of said traffic actuated means while right of way is accorded to said other lane, means in said mechanism to prolong accord of right of way to said one lane in response to further such actuation while right of way is accorded to said one lane, and means to retransfer right of way to said other lane within a time period if and after actuation ceases, and measured from the last such actuation, supervisory means connected to said mechanism and operating cyclically in a fixed and continuously repeated time cycle to cause at a predetermined point in each cycle the transfer of right of way from said one lane to said other lane despite such actuation of the traffic actuated means while right of way is on said one lane, and means forming a part of said supervisory means and operating in a predetermined part of such cycle including said predetermined point to prevent the control mechanism from transferring right of way from said other lane to said one lane in response to actuation on said one lane if the right of way is on said other lane.

3. A traffic control system for the intersection of interfering traffic lanes including signalling means adapted to accord right of way successively to the lanes, traffic actuated means in one of the lanes, a control mechanism to operate said signalling means to transfer right of way to said one lane from the other lane in response to actuation of said traffic actuated means while right of way is accorded to said other lane, means in said mechanism to prolong accord of right of way to said one lane in response to further such actuation while right of way is accorded to said one lane, and means to retransfer right of way to said other lane within a time period if and after actuation ceases, and measured from the last such actuation, and supervisory means connected to said mechanism and operating cyclically in a fixed and continuously repeated time cycle to cause at a predetermined point in each cycle the transfer of right of way from said one lane to said other lane despite further such actuation of the traffic actuated means while right of way is on said one lane,

means associated with said mechanism for storing the effect of any actuation on said one lane occurring within a predetermined period immediately prior to such transfer from said one lane by said supervisory means, and means forming a part of said supervisory means and operating for a predetermined part of said cycle including said predetermined point to prevent said mechanism from transferring right of way from said other lane to said one lane in response to actuation on said one lane if right of way is on said other lane.

4. In a traffic control system for the intersection of two interfering traffic lanes including a first traffic lane and a second traffic lane, signalling means to accord and interrupt right of way in the lanes, traffic actuated means in the lanes, and a cyclic signal switching mechanism having a plurality of positions through which it is adapted to be operated including at least one position for accord of right of way to said first lane and another position for according right of way to said second lane, a minimum timer device connected with said mechanism to maintain the latter in said first position to accord right of way to said first lane for a minimum period, said minimum timer device including a condenser, means including a connection with said mechanism for varying the charge on said condenser in said first position of said mechanism progressively from an initial value to a different final value, means including a connection with said mechanism and connected with the traffic actuated means of said first lane to be operated momentarily by traffic actuation therein to vary the charge on said condenser toward said initial value from any value between the said initial value and said final value in said first position, shifting means for transferring said mechanism from said first position to said second position when energized and having an energizing circuit including in series a switch closed by said mechanism in said first position, a switch closed by the traffic actuated means in said second lane by actuation therein, and an electronic tube adapted to pass sufficient current to operate said shifting means only responsive to the charge on said condenser reaching said final value, said last named switches and tube normally connecting said shifting means to said condenser to energize the shifting means responsive to the final charge on said condenser when the several series switches are closed, and an additional switch interposed in the said energizing circuit, and a time controlled cyclic operating device for said additional switch to close and open the latter alternately for definite time periods in continuously repeated time cycles much longer than said minimum period so as to interrupt said energizing circuit to prevent transfer of said signal switching mechanism from said first position in a certain part of each such time cycle and to prepare said energizing circuit for completion by traffic actuation in said second lane for such transfer in the remaining part of such cycle, and means including a further switch closed by said last mentioned cyclic device during at least a part of said time period when said additional switch is open in such cycle and also including a switch closed by said signal switching mechanism in its second position to connect said traffic actuated means of said first lane to said shifting means for direct energization of said shifting means by traffic actuation on said first lane to force im-

mediate transfer of said signal switching mechanism to said first position from said second position if in the latter position.

5. In a traffic control system for a plurality of intersections of interfering traffic lanes having at each intersection traffic actuated devices in said lanes and right of way according mechanism by which right of way is normally transferred from either one lane to the other lane for a minimum period in response to actuation of the said device on such other lane while right of way is accorded to said one lane and by which right of way is normally prolonged beyond said minimum on either lane in response to actuation of the device in that lane while right of way is accorded to that lane, supervisory means having a continuously operating time cycle of control for said mechanisms operating in predetermined time relation at the several intersections to prevent for a predetermined period in such cycle such transfer of right of way from a first of said lanes to the other in spite of actuation on such other lane and after a certain portion of said predetermined period has elapsed to cause transfer of right of way to said first lane from said other lane immediately in response to actuation on said first lane occurring at any time throughout the remainder of said predetermined period and in spite of any actuation on said other lane in the event right of way has been prolonged on said other lane into said predetermined period.

6. In a traffic control system for a plurality of intersections each of a first traffic lane with a second traffic lane, the combination, at each intersection, of signalling means to accord and interrupt right of way in the lanes, traffic actuated means in the lanes, and a control mechanism for operating said signalling means normally to transfer and prolong right of way alternately to said lanes in response to actuation of the respective traffic actuated means, and supervisory means to provide a continuously operating fixed time cycle of control over said control mechanisms and operating in predetermined time relation at the several intersections and including means operating throughout a time period extending over one part of such cycle to cause said control mechanism to transfer right of way to the first lane from the second lane substantially immediately in response to actuation of the traffic actuated means in said first lane occurring at any time throughout said time period while right of way is accorded to said second lane, said supervisory means also including means operating during another part of such cycle to permit the said normal operation by said control mechanism.

7. In a traffic control system for a plurality of intersections each of a first traffic lane with a second traffic lane, the combination, at each intersection of signalling means to accord and interrupt right of way in the lanes, traffic actuated means in the lanes, and a control mechanism for operating said signalling means normally to transfer and prolong right of way alternately to said lanes in response to actuation of the respective traffic actuated means, and supervisory means to provide a continuously operating fixed time cycle of control over said control mechanisms and operating in predetermined time relation at the several intersections and including means operating throughout a time period extending over one part of such cycle to

cause said control mechanism to transfer right of way to the first lane from the second lane substantially immediately in response to actuation of the traffic actuated means in said first lane occurring at any time throughout said time period while right of way is accorded to said second lane and means operating throughout a time period extending over a second part of such cycle to cause said control mechanism to transfer right of way to the second lane substantially immediately in response to actuation of the traffic actuated means of the second lane occurring at any time throughout said time period while right of way is accorded to said first lane, said supervisory means also including means for operating during a third part of such cycle between the first and second parts to permit the said normal operation by said control mechanism.

8. In a traffic control system for interfering traffic lanes having traffic actuated devices in said lanes and right of way according mechanism by which right of way is normally transferred from either one lane to the other lane for a minimum period in response to actuation of the said device on such other lane while right of way is accorded to said one lane and by which right of way is normally prolonged beyond said minimum on either lane in response to actuation of the device in that lane while right of way is accorded to that lane, supervisory means having a continuously operating time cycle of control for said mechanism to prevent for a predetermined period in such cycle such transfer of right of way from a first of said lanes to the other when right of way is on said first lane in spite of actuation on such other lane, and after a certain portion of said predetermined period exceeding said minimum has elapsed to cause transfer of right of way to said first lane from said other lane substantially immediately in response to actuation on said first lane occurring at any time throughout the remainder of said predetermined period and in spite of any actuation on said other lane if right of way has been transferred to said other lane before said predetermined period and is still retained on said other lane by actuation, said supervisory means including means operating for a second predetermined period after the first mentioned predetermined period to provide an assured period of said normal operation of said control mechanism before any further period of such transfer preventing or such immediate transfer action by said supervisory means.

9. In a traffic control system for intersecting traffic lanes having a traffic actuated device in one of said lanes and right of way according mechanism by which right of way is normally transferred to said one lane for a minimum period from another lane in response to actuation of said device while right of way is on such other lane and right of way is normally prolonged beyond said minimum in said one lane in response to actuation of said device while right of way is accorded to said one lane and right of way is normally retransferred to said other lane upon cessation of such prolonging actuation, supervisory means having a continuously operating time cycle of control for said mechanism to prevent for a predetermined period of major extent in such cycle such transfer of right of way to said one lane when right of way is on said other lane and after a certain portion of said

5 predetermined period exceeding said minimum has elapsed to cause transfer of right of way to said other lane substantially immediately despite such actuation of said device while right of way is accorded to said one lane if right of way has been transferred to said one lane prior to said predetermined period and right of way is still retained on said one lane by actuation, said supervisory means including means operating for 10 a second predetermined period after the first mentioned predetermined period to provide an assured period of said normal operation of said control mechanism before any further period of such transfer preventing or such immediate transfer action by said supervisory means.

10. A traffic control system for a series of intersections of cross traffic lanes with a common main traffic lane including in combination, traffic right of way control signals, traffic actuated means in the cross lanes, and time control mechanisms, all individual to each of the several intersections, each control mechanism including means for normally according right of way thru said signals to the main lane in absence of actuation of the traffic actuated means in its associated cross lane, and normally operating in response to such actuation to transfer right of way to such cross lane for a time period variable between a minimum and a maximum in accordance with the amount of such actuation during said period by prolonging the cross lane right of way for a time period from each of a series of such actuations repeatedly and thereafter to retransfer right of way to the main lane, and master control means including contact devices each connected to one of said mechanisms, and means for operating said contact devices cyclically in continuously repeated time cycles in predetermined progressive time phase relation with each other, and means in the several control mechanisms and operated by such contact devices progressively at the several intersections to prevent such normal transfer of right of way to the respective cross lanes for predetermined periods in such cycles and at predetermined points maintained in progressive time phase relation at the several intersections in said cyclic periods to cause immediate transfer of right of way from the respective cross lanes to the main lane if such transfer has not already occurred at such points, and during further predetermined periods in such cycles to permit the normal operation of said control mechanisms, whereby traffic moving progressively along the main lane will be assured predetermined periods of right of way progressively at the successive intersections.

11. In a traffic control system for the intersection of two interfering traffic lanes including a first traffic lane and a second traffic lane, the combination of signalling means to accord and interrupt right of way in the lanes, traffic actuatable means in the lanes, and control mechanism for operating said signalling means to transfer and accord right of way alternately to said lanes in response to actuation of the respective traffic actuatable means and to prolong right of way in a lane where it is being accorded upon further actuation of the traffic actuatable means in such lane, timing means in the control mechanism for determining a time period when operated, means in said control mechanism to cause transfer of right of way from the first lane to the second lane immediately at the completion of said time period in response to actuation on the

second lane when right of way is on the first lane and irrespective of actuation in the first lane, and supervisory means having a time cycle much longer than said time period during a predetermined part of which cycle it operates said timing means to assure transfer of right of way to said second lane in response to actuation in the latter in the event right of way is not already accorded to said second lane prior to expiration of said time period.

12. A traffic control system for the intersection of interfering traffic lanes including signalling means adapted to accord right of way successively to the lanes, traffic actuated means in one of the lanes, a control mechanism to operate said signalling means to transfer right of way to said one lane from the other lane in response to actuation of said traffic actuated means while right of way is accorded to said other lane, means in said mechanism to prolong accord of right of way to said one lane in response to such actuation while right of way is accorded to said one lane, timing means in said control mechanism for determining when operated a time period at the end of which it causes transfer of right of way to said other lane from the first lane by said mechanism when right of way is on said one lane irrespective of said actuation in said one lane, and supervisory means for cyclically in repeated time cycles initiating and maintaining operation of said timing means for a time interval at least as long as said time period in one part of each cycle and then rendering said time means inoperative during another part of each cycle.

13. A traffic control apparatus for an intersection of main and cross traffic lanes including in combination a right of way signal, traffic actuated means in the cross lane, and control mechanism for said signal for normally accord ing right of way to the main lane and operating normally to transfer in response to actuation of said means right of way to said cross lane, and timing means in said mechanism including a condenser, means for normally charging said condenser over a time period while right of way is accorded to said cross lane and means acting upon said condenser receiving a predetermined charge to cause retransfer of right of way to said main lane, and means operated by actuation of said traffic actuated means during such time period to discharge said condenser and thus prolong right of way on said cross lane, a second timing means in said mechanism including a second condenser, means for normally charging said second condenser over a time period longer than the time period of said first timing means and initiated into operation when right of way is transferred to the cross lane, and means acting upon said second condenser receiving a predetermined charge to cause retransfer of right of way to said main lane in spite of continued discharging of said first condenser, and a master control including means operating continuously and cyclically to cause at periodic intervals said control mechanism to supersede the normal charging of said second condenser and to charge said second condenser more rapidly than the normal charging thereof and so to retransfer right of way to said main lane at periodically spaced points in spite of such discharging means if the right of way is being so prolonged on said cross lane when such periodically spaced points occur.

14. In a traffic control system for the intersection of two traffic lanes including a first traffic lane and a second traffic lane, the combination of signalling means to accord and interrupt right of way in the lanes, traffic actuated means in the lanes, a control mechanism for operating said signalling means normally to transfer and accord right of way alternately to said lanes in response to actuation of the respective traffic actuated means and to prolong right of way by actuation of the traffic actuated means in a lane in which right of way is being accorded, supervisory means to provide a continuously repeated time cycle of control over said mechanism during a part of which cycle it conditions said mechanism to be operated by any actuation in said first lane and if right of way is on said second lane during such part of said cycle to transfer right of way to the first lane substantially immediately irrespective of actuation in said second lane, and means forming a part of said supervisory means and including a switch manually operable between open and closed conditions for rendering said mechanism so operated, only when said switch is in closed condition, to transfer right of way as soon as it is so conditioned as if actuation on said first lane occurred as soon as said mechanism was so conditioned.

15. A traffic control system for a plurality of intersections of two streets including signalling means adapted to accord right of way successively to the streets, traffic actuated means in the streets, control mechanism for operating the signalling means to transfer right of way for a minimum period to either street from the other street in response to actuation of the traffic actuated means in the first street and prolong such accord of right of way in response to further actuation on the first street, all at each intersection, and supervisory means connected to each said mechanism for providing a continuously repeated time cycle of control over said mechanism such cycle operating in predetermined time relation with corresponding cycles at the other intersections and having alternate periods in which right of way is preferred alternately on one street and the other in the presence of traffic as indicated by actuation, and forcing means operating whenever right of way is on one street during the period when right of way is preferred on the other street for conditioning said mechanism to transfer right of way to said other street substantially immediately in response to the first actuation occurring therein irrespective of actuation on said one street.

16. In a traffic control system for a plurality of intersections of cross lanes with a common main lane, the combination at each intersection of a right of way signalling device, traffic actuated means in the lanes and control mechanism for operating the signalling device thereat normally to transfer and accord right of way for a minimum period to either one lane from the other lane in response to actuation of the traffic actuated means in said one lane and to prolong such accord of right of way in response to further actuation on said one lane, supervisory means connected to each of the control mechanisms for providing a continuously repeated time cycle of control over said mechanisms such cycle having alternate periods in which right of way at each intersection is preferred alternately to the main and cross lanes thereat for establish-

ing a relationship of the right of way signals along the main lane for progressive movement of traffic thereon in the presence of such traffic, and forcing means connecting said supervisory means and said mechanism and operating whenever right of way is being so prolonged on one lane at an intersection during the period when right of way is preferred on the other lane at such intersection for transferring right of way to said other lane substantially immediately in response to actuation on said other lane irrespective of actuation on said one lane.

17. A traffic control system for the intersection of two streets including signalling means adapted to accord right of way successively to the streets, traffic actuable means in one of the streets, control mechanism for operating the signalling means normally to accord right of way to the other street and in response to actuation of the traffic actuable means in said one street to transfer right of way to said one street for a minimum period and to prolong such accord of right of way beyond said minimum in response to further actuation of said traffic actuable means, supervisory means for providing a continuously repeated time cycle of control over said mechanism, and including means operable at a predetermined point in said cycle if right of way is being accorded to said one street to cause said mechanism to transfer right of way immediately for at least a minimum period to said other street, and means forming a part of said supervisory means and operating for a period immediately preceding said point and exceeding the minimum period for said one street to prevent transfer of right of way to said one street during said last named period in response to actuation if right of way is on said other street.

18. In a traffic control system for a plurality of intersections of cross lanes with a common main lane, the combination at each intersection of a right of way signalling device, traffic actuable means in the lanes and control mechanism for operating the signalling device thereat normally to transfer and accord right of way for a minimum period to either one lane from the other lane in response to actuation of the traffic actuable means in said one lane and to prolong such accord of right of way in response to further actuation on said one lane, supervisory means connected to each of the control mechanisms for providing a time cycle of control over said mechanisms such cycle having alternate periods in which right of way at each intersection is preferred alternately to the main and cross lanes thereat for establishing a relationship of the right of way signals along the main lane for progressive movement of traffic thereon in the presence of such traffic, forcing means connecting said supervisory means and said mechanism and operating when right of way is being so prolonged on one lane at an intersection during the period when right of way is preferred on the other lane at such intersection for transferring right of way to said other lane substantially immediately in response to actuation on said other lane irrespective of actuation on said one lane, and means forming a part of said supervisory means operating for a predetermined time prior to such period when right of way is preferred on said other lane to prevent such normal transfer of right of way from said other lane to said one lane in the event that such transfer has not already occurred prior to said time, whereby sufficient time will be provided to allow for a mini-

5 mum period of right of way on said one lane in the event that transfer of right of way to said one lane occurs immediately prior to such period of prevent of transfer.

19. A traffic control system for the intersection of interfering traffic lanes including signalling means adapted to accord right of way successively to the lanes, traffic actuable means in one of the lanes, a control mechanism to operate said signalling means to transfer right of way to said one lane from another lane in response to actuation of said traffic actuable means while right of way is accorded to said other lane, means in said mechanism to prolong accord of right of way to said one lane in response to further such actuation while right of way is accorded to said one lane, timing means in said mechanism initiated into operation when right of way is accorded to said one lane and normally connected to said mechanism for providing a maximum time limit to prolongation of right of way on said one lane, supervisory means for providing a cycle of control over said control mechanism and means operating at a predetermined point in said cycle to interrupt such normal connection of said timing means and to connect said timing means to time a predetermined period during which transfer of right of way from said other lane to said one lane in response to actuation is prevented and at the end of which transfer of right of way to said other lane is assured if right of way is not already on said other lane.

20. In a traffic control system for the intersection of two interfering traffic lanes including a first traffic lane and a second traffic lane, signalling means to accord and interrupt right of way in the lanes, traffic actuated means in the lanes, and a cyclic signal switching mechanism having a plurality of positions through which it is adapted to be operated including at least one position for accord of right of way to said first lane and another position for according right of way to said second lane, a minimum timer device connected with said mechanism to be energized by the latter in its said first position to maintain said mechanism in said first position according right of way to said first lane for at least a minimum period and connected normally to condition said mechanism at the end of such minimum period for transfer to said second position to transfer right of way to said second lane in response to actuation of the traffic actuated means in said second lane, means including a connection with said mechanism in said first position and the traffic actuated means of said first lane to interrupt the normal timing operation of said timer device momentarily by actuation in said first lane to postpone such conditioning so as to prolong right of way on said first lane beyond said minimum, a supervisory switch device operating in continuously repeated time cycles of length much greater than said minimum time period in a first part of which cycle right of way is preferred to said first lane and in a second part of which cycle right of way is preferred to said second lane and in intervening parts of which cycle there is no preference for either lane, said supervisory device also including switching means operated in said first part of such cycle and connected to said mechanism to interrupt such conditioning of said mechanism by said minimum timer in said first position so as to prevent transfer of right of way from said first lane in said first part of such cycle if said mechanism is in said first position according right of

way to said first lane, said supervisory device also including switching means operated in at least a portion of said first part of said cycle for connecting the traffic actuated means of said first lane to said mechanism in said second position directly to transfer said mechanism to its

first position immediately in response to actuation on said first lane to force transfer of right of way to said first lane if said mechanism is then in said second position according right of way to said second lane.

HARRY A. WILCOX.
